UNITED STATES PATENT OFFICE

ANGUS J. HATT, OF ROCK SPRINGS, WYOMING, ASSIGNOR, BY MESNE ASSIGNMENTS, TO
GOODMAN MANUFACTURING COMPANY, OF CHICAGO, ILLINOIS, A CORPORATION OF
ILLINOIS

CONVEYER

Application filed March 13, 1929. Serial No. 346,650.

The present invention relates to conveyers, particularly sectional shaker conveyers, and has for its object the provision of a conveyer construction wherein connection and disconnection of adjoining conveyer sections may be effected much more quickly than heretofore.

The common practice has been to connect the conveyer sections to one another by means of bolts and nuts, the bolts extending through corresponding perforate lugs or ears provided for the purpose at the ends of the sections. Naturally, placement of the bolts in the lugs and screwing up the nuts to draw the sections together when they are being assembled, or, unscrewing of the nuts and removal of the bolts when sections are being disconnected, takes considerable time, resulting in delays in the removal or addition of conveyer sections to suit the particular conditions under which the conveyer is being used. These delays are particularly objectionable and costly in coal mining operations to which the shaker type of conveyer is especially adapted and in which field it is now in extensive use. With the present invention, the time necessary to connect or disconnect the conveyer sections is reduced to a minimum.

With the old nut and bolt connection between the sections, frequently it is found difficult to assemble conveyer sections properly, when the sections and the fastening lugs or ears are bent or otherwise distorted. Under these conditions it is difficult to properly align the perforate lugs in order to place the bolts in position therein without damaging them so that the nuts cannot be put in place. In the proposed arrangement, it is intended that the fastening means, when in place, shall serve not only to draw the lugs closely together, but also to cause the lugs to be properly aligned with reference to each other so that the adjoining conveyer sections will properly overlap and nest one within the other.

A particular object of the invention is the provision of means for connecting the conveyer sections which shall render it unnecessary to change the conventional construction of the sections. Thus, the connecting means may be applied to the many units of this and similar types already in use.

In order that the connecting or fastening means may be applied or removed quickly, as few parts as possible are used and their mode of assembling and disassembling is quite simple, so as not to require the employment of skilled help or the use of special tools. All of the fastener parts are designed to fully withstand the stresses to which they may be subjected in use, and, in fact, furnish a connection between the conveyer sections as strong as, and possibly stronger than, that provided by the usual bolts and nuts. Other objects of the invention will appear herein-
after.

In the accompanying drawing, which illustrates a practical embodiment of the invention,

Figure 1 represents a side elevational view of a pair of adjoining shaker conveyer sections of the conventional or standard type with the improved joint or connection therebetween;

Fig. 2, a transverse section taken on line 2—2 of Fig. 1, showing the manner in which the perforate lugs or ears are located on the conveyer sections;

Fig. 3, an enlarged side elevational view of one of the fastening devices as it appears when assembled, certain of the parts being broken away and the cooperating pair of perforate lugs being shown in longitudinal section, so as to show the relationship between the various parts when the device is in use; and

Fig. 4, an enlarged perspective view of the three parts which go to make up each of the fastening devices, the parts being disassem-

bled in order to show the details of their constructions.

Referring to Figs. 1 and 2, there is shown a pair of adjoining shaker conveyer sections 1, 2 of conventional construction. The cross sectional form of these sections appears clearly in Fig. 2, from which it will be noted that each section, which is made from heavy gage sheet metal, is formed so as to have outwardly inclined sides 3, 4. Both of the sides of the section are stepped or offset intermediate their edges in order to provide a horizontal ledge or shoulder 5. The upper edges of the sides are formed with integral horizontal portions 6, while the bottom of the conveyer section or pan is made flat as shown at 7.

Suitably secured to the conveyer section near each end thereof is the usual bolt strap 8, which is preferably made of strap iron. As appears from Fig. 2, strap 8 bears against the under side of bottom 7 of the pan or conveyer section and at its ends is bent so as to form lugs or ears 9, 10 having longitudinally disposed openings therethrough. The extreme ends of bolt strap 8 are bent upwardly and are suitably secured, as by rivets 11, to angle plates 12, 13, the latter being secured, as by welding, to the under side of offsets 5 in the sides of the conveyer section.

It will be noted from Fig. 1 that the bolt straps 8 are duplicated on the ends of each of the conveyer sections or pans. In the same figure, it will be seen, that where the adjoining conveyer sections are connected together one of the bolt straps 8 which is included in this connection, is located at the extreme end of its section, so that its outer edge is flush with the end of the pan. The cooperating bolt strap 8 on the adjoining conveyer section which is included in this connection however, is set back a short distance from the end of its section, so that the conveyer sections may overlap somewhat and partially nest one within another as shown at 14 in Fig. 1.

Bolt straps 8 on the various conveyer sections are so proportioned that, when proximate sections are brought together as shown in Fig. 1, the openings or perforations in lugs or projections 9, 10 of the bolt straps will be in alinement with each other.

With the adjoining conveyer sections or pans 1, 2 in position as shown in Fig. 1, the corresponding or adjoining lugs 9 and 10 are ready to receive the fastening means. A separate set of fastening means or a separate fastening device is provided for each pair of cooperating lugs, one for one side of the conveyer and another for the opposite side at the points of connection of the sections.

Each fastening device comprises three members, viz., a pin 15, a link or strap 16 and a taper key or wedge 17. The preferred form and construction of these members ap-

pears clearly in Figs. 3 and 4. Pin 15, which is substantially circular in transverse section, is formed with an elongated straight body portion 18 the free end 19 of which is slightly tapered at 19'. At its opposite end pin 15 is bent back upon itself so as to form a semi-circular lug-engaging or clamping end portion 20. Beyond this point, pin 15 is provided with a substantially straight portion 21 which is approximately parallel to, but spaced somewhat from the body portion 18. The outer extremity 22 of pin 15 beyond straight portion 21 is inclined upwardly away from the body portion 18 of the pin and towards the free end thereof. While the several portions of pin 15 are bent relatively to each other as described, it will be noted that they all are disposed substantially in a single plane.

Referring further to Figs. 3 and 4, it will be seen that the inclined end 22 of pin 15 is provided with a transverse opening 23, which opening however extends longitudinally of the body of the pin. Preferably opening 23 is rectangular in cross-section in order to properly coat with the other parts of the fastener. The purpose of the bevelled portion 24 on the inclined end 22 of the pin will appear later.

With a pair of conveyer sections substantially in the position of Fig. 1, the free end 19 of the pin is inserted in the outer end of the opening through the left-hand ear or lug 9, and, with the aid of a hammer or any other suitable implement applied to portion 20 of the pin, the pin is driven through the opening in this lug and into the opening in the adjoining lug, until the semi-circular portion 20 of the pin is brought into contact with the outer end of the first-mentioned lug, see Fig. 3. The entering of end 19 of the pin into the openings through the lugs, will be facilitated by the presence of the tapered portion 19' at the extremity of the pin. Particularly will this be so where the lugs are somewhat out of alinement, due to bending of the pans or other similar causes.

The next step is to secure the strap or link 16 in place. The body portion 25 of this member is substantially straight and of elongated form. Preferably, it is rectangular in transverse section, the width of the member being considerably greater than its thickness, as appears from Fig. 4. At its right-hand end link 16 is bent downwardly so as to form a lug-engaging or clamping hook portion 26 the free extremity 27 of which is substantially circular in vertical cross-section and somewhat tapered so as to properly cooperate with the opening through the right-hand lug 9 in which it is placed as shown in Fig. 3. When the hook end 26 of link 16 is so located in the right-hand lug 9, the opposite end thereof is swung inwardly toward the lugs, so as to cause the inclined end 22 of pin 15 to enter

the circular opening 28 in the body of link 16 and project therethrough, for which also see Fig. 3. Passage of end 22 of pin 15 through opening 28 is facilitated by the inclined surface 24 on the end of the pin. When 5 the parts of the fastener are in this position, note that the lower portion of the body of link 16 at the bottom of opening 28 therein is in contact at 29, Fig. 3, with the left-hand side of the inclined portion 22 of pin 15.

The next and last step is the placing in position of the third member of the fastening device, namely, key or wedge 17. This member, as shown in Fig. 4, is preferably rectangular in vertical cross-section and tapers toward its free end 30, the opposite end thereof being bent substantially at right angles to the body of the member so as to form a head or driving portion 31. The free end 30 of the key 17 is placed in the right-hand end of opening 23 in the upper end of pin 15 above the link 16, as shown in Fig. 3, and, with the aid of a hammer or other suitable tool applied to its head 31, the wedge 17 is 25 driven through the opening. Movement of the wedge through opening 23 results in the wedge forcing the body portion 25 of link 16 downwardly on the inclined upper end 22 of pin 15. Opening 28 in link 16 is made sufficiently large to permit movement of the inclined end 22 of pin 15 therethrough, but the parts are so proportioned that the engagement of link 16 with pin 15 at 29 will continue. It will be clear that, due to this engagement of the link with the inclined end 35 22 of the pin, the downward swinging movement of the left-hand end of link 16 as wedge 17 is driven into place will result in a longitudinal drawing together or shortening of the 40 over all length of the cooperating pin 15 and link 16. Consequently, since the last-mentioned members are securely engaged with the open ends of the adjoining lugs 9, this action of the members 15 and 16 not only will 45 cause the lugs to be drawn into firm end to end engagement with each other, but the lugs also will be properly aligned with each other.

Frequently, due to the rough usage to which they are subjected, the conveyer sections are bent or otherwise distorted, so that, when they are assembled the cooperating lugs 50 9, 10 are not in alinement. This renders it difficult to fasten the conveyer sections together and prevents proper nesting of the 55 sections at their joints. With one of the fastening devices herein described applied to each side of the conveyer, the cooperating pairs of lugs 9, 10 are drawn into their proper positions, as shown in Fig. 1 and the pan or 60 conveyor sections are held rigidly in correct relation to each other.

Alinement of the coating lugs 9, 10 when the fastening means are in place, is assured by the proper shaping and proportioning of 65 the several parts, so that when they are in

place, they will assume the relationship to each other shown in Fig. 3.

When it is desired to disconnect adjoining conveyer sections, as for instance when it is necessary to shorten the conveyer, the fastening means described are readily removed by driving out the wedge 17, swinging up the straight end of link 16, and removing this member and pin 15 from the fastening lugs. 70

While the fastening means have been described with the pin inserted at the left-hand side of the adjoining fastening lugs, it will be obvious that the pin may be inserted from the right-hand side and the other parts reversed accordingly. 75

The present invention provides a conveyer construction in which a highly desirable type of joint or connection is employed between the sections of the conveyer, whereby assembling and disassembling of conveyer sections is facilitated. The fastening means used in connecting the sections together is of simple construction and therefore may be manufactured readily on a quantity production basis. 80

While a practical embodiment of the invention has been illustrated and described, it will be apparent that various changes therein may be made without departing from the invention. Hence, the claims are to be 85 read without restriction to minor details unless such limitation be expressed therein.

What is claimed is:

1. In a conveyer, the combination of two conveyer sections assembled in end-to-end relation with one another; perforate lugs on respective sections said lugs being juxtaposed when the sections are assembled; a pair of fastening members each having a portion which engages in the perforation in a corresponding one of two juxtaposed lugs, and a portion external to said lugs; and adjustable means external to said lugs for connecting the external portions of said fastening members and stressing them in tension. 100

2. The combination in a conveyer, of a pair of conveyer sections disposed end to end, said sections being provided with cooperating perforate fastening lugs; and a pair of adjustably connected members one of which 105 has a lug-engaging portion and the other an end portion located in the perforations in said fastening lugs. 110

3. In a conveyer, the combination of two conveyer sections assembled in end-to-end relation with one another; perforate lugs on respective sections said lugs being juxtaposed when the sections are assembled; a pair of fastening members each having a portion which engages in the perforation in a corresponding one of two juxtaposed lugs, and a portion external to said lugs; means 120 affording a wedging engagement between the external portions of said fastening members 125 to establish a tensile stress; and a member 130

distinct from said fastening members and operable to force said members into such wedging engagement.

4. In a conveyer, the combination of two 5 conveyer sections assembled in end-to-end relation with one another; perforate lugs on respective sections said lugs being juxtaposed when the sections are assembled; a pair of fastening members each having a portion 10 which engages in the perforation in a corresponding one of two juxtaposed lugs, and a portion external to said lugs; means affording a wedging engagement between the external portions of said fastening members 15 to establish a tensile stress; and a wedge member distinct from said fastening members and reacting with said members to force them into wedging engagement with one another.
- 20 5. A conveyor comprising a pair of conveyer sections disposed end to end in overlapping relation; a plurality of perforate fastening lugs on each of said sections with corresponding lugs located adjacent each 25 other; a main fastening member for each pair of corresponding lugs, the shank of each of said members being located within the openings of said pair of lugs and the outer end of the member being perforated; a secondary fastening member for each pair of 30 corresponding lugs, one end of each of said secondary members being hook-shaped and engaging the opening in one of said pair of lugs, the other end of the secondary member 35 being perforated to receive the outer perforate end of the corresponding main fastening member; and a tapered pin located in the perforate end of each of the main fastening members.
- 40 6. The combination in a conveyer, of a pair of adjoining conveyer sections provided with a pair of perforate fastening lugs; a pin having a substantially straight body portion located in the perforations in said 45 pair of lugs, the outer end of the pin being inclined with reference to said body portion and having an opening therethrough; a link engaging at one end with one of said pair of lugs and provided with an opening 50 through which the inclined end of the pin projects; and a wedge located in said opening in the pin between said link and the outer end of the pin.
- 55 7. The combination in a conveyer, of a pair of adjoining conveyer sections, said sections being provided with perforate fastening lugs disposed end to end; a pair of adjustably connected fastening members each of which has a portion engaging one of said 60 pair of lugs, one of said members at the point of connection thereof being provided with an inclined surface which coacts with the other member to draw the members and the lugs together; and means for forcing 65 one of the fastening members into wedging

engagement with said inclined surface of the other member.

8. In a conveyer construction, the combination of a pair of adjoining conveyer sections having a pair of perforate fastening lugs with the openings therethrough disposed in alignment with each other; a pin having a straight body portion extending entirely through the opening in one of said lugs and partially through the opening in the other lug, the outer end of the pin being bent back upon itself so as to overlie the first-mentioned lug and having its outer extremity disposed at an angle to its body portion, said extremity having an opening therethrough; a link one end of which is provided with a hook engaging the opening in the second-mentioned lug, while the body of the link has an opening therein through which the inclined extremity of the pin projects; and a wedge shaped key driven into the opening in said inclined extremity of the pin between the link and the outer end of the pin.

9. A fastener for connecting conveyer sections having fastening lugs with aligned apertures, comprising in combination, a pair of hooks, one of which hooks extends into and is confined in the aperture in one lug, and the other of which engages freely in the aperture in the other lug, said hooks being so formed as to enter into wedging engagement with each other to draw the lugs together when the second hook is forced laterally relatively to the first; and means for forcing said second hook in such lateral direction.

10. A fastener for connecting conveyer sections having fastening lugs with aligned apertures, comprising in combination, a pair of hooks, one of which hooks extends into and is confined in the aperture in one lug and extends therethrough into aligning engagement with the aperture in the other lug, and the other of which engages freely in the aperture in the other lug, said hooks being so formed as to enter into wedging engagement with each other to draw the lugs together when the second hook is forced laterally relatively to the first; and means for forcing said second hook in such lateral direction.

11. A fastener for connecting conveyer sections having fastening lugs with aligned apertures, comprising in combination a pair of hooks, one of which hooks extends into and is confined in the aperture in one lug, and the other of which engages freely in the aperture in the other lug, said hooks being so formed as to enter into wedging engagement with each other to draw the lugs together when the second hook is forced laterally toward the first; and a wedge reacting between portions of said hooks to force them laterally toward one another.

12. A fastener for connecting conveyer sections having fastening lugs with aligned apertures, comprising in combination a pair of hooks, one of which hooks extends into and is confined in the aperture in one lug and extends therethrough into aligning engagement with the aperture in the other lug, and the other of which engages freely in the aperture in the other lug, said hooks being so formed as to enter into wedging engagement with each other to draw the lugs together when the second hook is forced laterally toward the first; and a wedge reacting between portions of said hooks to force them laterally toward one another.

13. A fastener for adjoining conveyer sections having perforate fastening lugs, comprising a pair of fastening members having hook-shaped portions for engaging with the openings in said lugs, said members being adapted for adjustable connection with the fastener extending across the line of separation between said lugs exteriorly thereof.

14. A fastener for adjoining conveyer sections having perforate fastening lugs, comprising a pair of members adapted for engagement at their outer ends in said perforated lugs; and means for connecting said members together at their opposite ends, said fastener being adapted to extend across the line of separation between said lugs exteriorly thereof.

15. A fastener for adjoining conveyer sections having perforate fastening lugs, comprising a member having a shank adapted to be mounted in the opening in one of said lugs and a perforate arm inclined relative to said shank; a second member having a hooked end adapted to be located in the opening of the lug adjoining said first-mentioned lug and perforated at its opposite end to freely receive said inclined arm of the first-mentioned member; and a tapered key adapted to be located in the opening in said inclined arm above the perforate end of the second-mentioned member.

16. A fastener for connecting conveyer sections having contacting fastening lugs with aligned apertures, comprising in combination, a pair of hooks, one of which hooks extends through the aperture in one lug into aligning engagement with the aperture in the other lug, and the other of which hooks engages freely in the aperture in said other lug and has a portion which extends past the plane of contact of said lugs externally of the lugs and enters into wedging engagement with the first hook to draw the hooks and the lugs engaged thereby together.

17. A fastener for connecting conveyer sections having contacting fastening lugs with aligned apertures, comprising in combination, a pair of hooks, one of which hooks extends through the aperture in one lug into aligning engagement with the aperture in the

other lug, and the other of which hooks engages freely in the aperture in said other lug and has a portion which extends past the plane of contact of said lugs externally of the lugs and enters into wedging engagement with the first hook to draw the hooks and the lugs engaged thereby together; and a wedge key for forcing said hooks into such wedging engagement.

In testimony whereof I have signed my name to this specification.
